CLAIM

The ornamental design for a lactation chair, as shown and described.

DESCRIPTION

FIG. 1 is a perspective view of a new design for a lactation chair;

FIG. 2 is a front plan view of the lactation chair of FIG. 1; FIG. 3 is a rear plan view of the lactation chair of FIG. 1; FIG. 4 is a first side plan view of the lactation chair of FIG. 1;

FIG. 5 is a second side plan view of the lactation chair of FIG. 1;

FIG. 6 is a top plan view of the lactation chair of FIG. 1; and, FIG. 7 is a bottom plan view of the lactation chair of FIG. 1.

The broken lines shown in the drawings are for the purpose of illustrating environmental structure and form no part of the claimed design.
